DESIGN FOR A KNIFE

Raebelle Wagner, Freehold, N. J.

Application March 9, 1944, Serial No. 112,838

Term of patent 14 years

(Cl. D22—3)

To all whom it may concern:

Be it known that I, Raebelle Wagner, a citizen of the United States, residing in the city of Freehold, county of Monmouth, and State of New Jersey, have invented a new, original, and ornamental Design for a Knife, of which the following is a specification, reference being had to the accompanying drawing, forming a part thereof.

I claim:

The ornamental design for a knife, as shown.

RAEBELLE WAGNER.
